UNITED STATES PATENT OFFICE.

ROBERT C. SAUER, OF LOUISVILLE, KENTUCKY.

DRAFTING INSTRUMENT.

No. 858,913.

Specification of Letters Patent.

Patented July 2, 1907.

Application filed January 30, 1907. Serial No. 354,879.

To all whom it may concern:

Be it known that I, ROBERT C. SAUER, a citizen of the United States of America, residing at Louisville, in the county of Jefferson and State of Kentucky, have 5 invented new and useful Improvements in Drafting Instruments, of which the following is a specification.

This invention relates to a combination drafting instrument whereby straight or curved lines, circles, and lines at various angles can be conveniently and readily 10 made or arcs and angles of any degree accurately and quickly measured.

The invention has for one of its objects to provide an instrument of this character in which the means for accomplishing the various operations above mentioned 15 is combined with a T-square of approved construction.

A further object of the invention is the provision of a T-square upon which is slidably mounted hingedly connected scale blades whereby circles or arcs of circles of various radii, lines at any desired angle and arcs 20 and angles may be measured in degrees with great facility without the use of the usual divider compass, beam compass, triangles and protractors.

Another object of the invention is to improve and simplify the construction and operation of devices of 25 this character so as to be comparatively easy and inexpensive to manufacture, readily and conveniently manipulated, composed of few parts and designed to enable the scale blades to be folded under the blade of a T-square out of the way when not in use.

30 With these objects in view as will appear as the nature of the invention is better understood, the invention comprises the various novel features of construction and arrangement of parts which will be more clearly described hereinafter and set forth with particularity in the claims appended hereto.

In the accompanying drawing which illustrates one of the embodiments of the invention Figure 1 is a plan view of the instrument with portions of the T-square head and blade broken away. Fig. 2 is a transverse 40 section on line 2-2, Fig. 1, showing the scale blades in elevation. Fig. 3 is a vertical transverse section on line 3-3, Fig. 1, drawn on a slightly enlarged scale. Fig. 4 is a similar section on line 4-4, Fig. 1.

Corresponding parts are indicated by similar reference characters through the several views of the drawings.

Referring to the drawing, 1 designates a T-square consisting of the usual head 2 and the blade 3, which is preferably a steel casting secured to the head 1 by 50 screws or other suitable fastenings 4. The blade 3 is provided adjacent the ruling edge 5 with a slot 6 that extends approximately the full length thereof. The under side of the blade is formed with longitudinal ribs 7 which, besides serving to reinforce and stiffen the 55 blade, raise the blade off the drawing board so as to accommodate the scale blades when the latter are folded

into an inoperative position, as when they are not required and the instrument is to be used as an ordinary T-square.

Employed in combination with the T-square is a pair 60 of scale blades 8 and 9 having their adjacent ends arranged in overlapping relation and hingedly connected by the rivet 10. These blades have perfectly straight and smooth longitudinal edges and any desired system or systems of divisions or scales may be applied thereto. 65 Each blade is provided with an elongated rectangular slot 11 extending approximately the full length thereof. Arranged to slide in one or the other of these slots 11 is a pen or pencil holder designated generally by 12. This holder comprises an axially bored screw or bolt 13 having a rounded portion 14 that fits slidably in the slot 11 and engaging the thread 15 is a nut 16 bearing on one side of the blade 8 or 9 with the head 17 of the screw bolt bearing on the opposite side. By loosening the nut 16 the pencil holder can be adjusted to any desired position and then secured in place by tightening the nut. 70 To change the pencil holder from one scale blade to the other it is, of course, necessary to unscrew the nut entirely and take out the bolt and adjust the holder to the desired blade. The rivet 10 is preferably provided 75 with an opening 18 for facilitating the obtaining of centers and other points in the various operations of the instrument.

The scale blade 8 is slidably and pivotally mounted 80 on the blade of the T-square by means of a slide 19 and a pivot lug on the blade 8 passing through the slide. The slide comprises a semi-circular plate having lugs 20 curled downwardly to enter the slot 6 of the T-square blade as best shown in Fig. 2, the fit being such that a perfectly rigid and accurate movement of the slide 19 is 85 possible. Adjacent the periphery of the slide 19 are arranged degree marks designated by 21 after the fashion of an ordinary protractor. The scale blade 8 which is preferably cast steel has the pivot lug 22 formed integral therewith and projects upwardly through the slide 19 and through a flat quadrant shaped plate 23. The lug 22 is transversely apertured to receive the pivot pin 24 for the clamping cam 25, said cam being provided with a lever 26 for conveniently operating the cam. This cam forms a clamping means whereby the scale blade 8 90 and slide 19 are securely fastened in any desired position of adjustment. The quadrant 23 has an index mark 27 coinciding with its center line which co-operates with the scale 21 of the slide 19 for adjusting the scale blades to any desired angle and for measuring an 95 angle or arc in terms of degrees. In the center line of the quadrant 23 is a depression 28 for receiving the laterally curved end of the cam lever 26, as best shown in Fig. 2.

From the foregoing description taken in connection 100 with the accompanying drawing, the advantages of the construction and of the method of operation will be

readily appreciated by those skilled in the art to which the invention appertains. Various methods of operation will readily suggest themselves to draftsmen, carpenters and others having use for such an instrument. 5 Some of these methods will now be briefly described.

When the instrument is to be used as an ordinary T-square the blade 9 is first folded over the blade 8 and then the cam 25 is unclamped so that the scale blades can be swung under the T-square blade. The clamp- 10 ing cam is then tightened so as to hold the blades in place. Horizontal lines can then be drawn by the use of the T-square blade in the usual manner. When it is desired to draw vertical lines or lines between the vertical and horizontal, the scale blades 8 and 9 are em- 15 ployed. To draw circles of large radii the pivot 22 is used at its center and a pencil is placed in the holder 12 and the lines drawn by swinging the scales 8 and 9 as a single member or unit around the pivot 22. By adjust- 20 ing the holder 12 back or forth on either one of the scale blades concentric circles can be described. In order to draw circles of small diameters the opening 18 in the rivet 10 is used as a center and the blade 9 is swung around to describe the circle while the pencil is held in the holder 12. By shifting the holder concent- 25 ric circles or arcs can thus be described. To measure an angle or the length of an arc or circle in degrees the instrument is adjusted so that the axis of the pivot 22 will coincide with the center of the arc or angle and then the scale blade or blades are manipulated after 30 first loosening the clamping cam. For instance, the scale blade is moved so as to coincide with one end of the arc to be measured, and then the quadrant plate 23 is adjusted so that the lever 26 will enter the depression 28 when the cam is tightened. The position of the index line 27 on the quadrant is noted with relation to the degree scale 21. The clamping cam is then loosened and the scale blade adjusted to the opposite end of the arc to be measured. The quadrant plate 23 is again 35 shifted so that the clamping cam can be tightened and the lever 26 thereof enter the depression 28 of the quadrant plate. The position of the index line 27 with respect to the scale 21 is noted so that by a simple computation the length of the arc in degrees is obtained.

From the foregoing it will be seen that the instrument 40 is adapted to a large variety of uses, and obviates the need of several ordinary drafting implements, such as triangles, scale rule, protractor, compasses and the like.

I have described the principle of operation of the invention together with the apparatus which I now consider to be the best embodiment thereof, and I desire to 45

have it understood that the apparatus shown is merely illustrative and that various changes may be made when desired as are within the scope of the claims.

What I claim is:

1. In an instrument of the class described, the combination of a T-square, a slotted blade pivotally and slidably mounted on the blade of the square, and a pencil holder slidable on the slotted blade, said holder comprising a longitudinally bored screw bolt, and a nut engaging the bolt. 55

2. In an instrument of the class described, the combination of a T-square having a slotted blade, a slide movable on the top surface of the blade and provided with means engaging in the slot of the T-square blade, a pair of hingedly connected scale blades pivotally mounted on the slide, and a clamping means for adjustably securing the slide and scale blades to the T-square blade. 60

3. In an instrument of the class described, the combination of a slotted blade provided with longitudinal ribs on its under surface, and a longitudinal slot, a slide movable on the top surface of the blade, a blade pivotally mounted on the slide and arranged to fold under the slotted blade, and a clamping means for adjustably securing the slide and second blade in fixed position on the slotted blade. 70

4. In an instrument of the class described, the combination of a T-square having a longitudinally slotted blade, a slide on the blade having portions engaging the slot of the latter, a second blade, a pivot thereon extending through the slide from the underside of the square blade, a plate 80 on the slide through which the pivot extends, a clamping cam fulcrumed on the pivot for clamping the slide and second blade to the square blade. 75

5. In an instrument of the class described, the combination of a T-square having a slotted blade, a semi-circular slide movable along the blade and provided with portions engaging in the slot of the latter, a degree scale on the slide adjacent the periphery thereof, a plate movably mounted on the slide and provided with an index mark and having a depression in line with said mark, a slotted 85 secondary blade disposed under the square blade and provided with a lug extending upwardly through the slide and plate, a clamping device on the lug adapted to engage in the depression of the plate, and a pencil holder adjustably mounted on the secondary blade. 90

6. In an instrument of the class described, the combination of a T-square having a slotted blade, a slide guided by the slot, a slotted blade pivotally mounted on the slide, a third slotted blade arranged with one end overlapping the second blade, a hinge connecting the overlapping portions of said blades and provided with an opening, and a pencil holder adapted to be used interchangeably on either of the hingedly connected blades. 100

In testimony whereof, I affix my signature in presence of two witnesses.

ROBERT C. SAUER.
